UNITED STATES PATENT OFFICE.

SERGE KANSCHINE, OF NICE, FRANCE, ASSIGNOR OF ONE-HALF TO EMIL JELLINEK-
MERCEDES, OF NICE, FRANCE.

TYPE-WRITING MACHINE.

1,003,361.

Specification of Letters Patent. Patented Sept. 12, 1911.

Application filed May 27, 1911. Serial No. 629,844.

To all whom it may concern:

Be it known that I, SERGE KANSCHINE, subject of the Emperor of Russia, residing at Nice, in the Republic of France, have invented certain new and useful Improvements in Type-Writing Machines, of which the following is a specification, reference being had therein to the accompanying drawing.

10 The present invention has for its object a special construction of the keyboard of ordinary writing machines with the object of enabling plain or open writing to be transposed into cipher writing or inversely 15 of transposing cipher writing into ordinary text, the arrangement being such that it is possible to adapt the cipher writing and the deciphering to changing cipher keys.

The arrangement consists in the fact that 20 the keys of a writing machine, which are marked correspondingly with the type levers with normal or cipher characters or with both of them, are formed in such a manner, that small plates or caps which carry either 25 normal characters or cipher characters can be interchangeably secured thereto.

Figure 1 of the accompanying drawing illustrates in plan the keyboard of a writing machine serving for cipher writing.

30 Fig. 2 is a section of a key on a larger scale. Fig. 3 shows the keyboard of a writing machine serving for deciphering. Fig. 4 is a view similar to Fig. 2. Fig. 5 shows the keyboard of a writing machine serving both 35 for writing in cipher and for deciphering.

Any known type of type writing machine can be employed. In the machine intended for writing in cipher which is illustrated in Fig. 1, the key plates m and type-levers (not 40 shown in the drawings) are correspondingly provided with the cipher characters employed, such for example as 21, 36, 45 and so forth; each of the key-plates m mounted on one of the key levers n is provided with 45 a rectangular hole o . In combination with the writing machine thus constructed a series of small plates a is provided which carry writing or numeral characters; the size of these plates corresponds to that of 50 the surface of the key plates m while on their under side they are provided with a rectangular pin t adapted to fit into the angular hole o on each of the key plates m . In order to transpose ordinary matter into

cipher by means of this machine the loose 55 plates carrying the ordinary characters are arranged upon the key plates m in accordance with the cipher key selected so that the keyboard now corresponds with the keyboard of an ordinary writing machine. 60 When it is operated, however, it writes in cipher text and not in ordinary text.

The keyboard of the deciphering machine illustrated in Fig. 3 corresponds entirely with that of an ordinary writing machine 65 and the ordinary characters are provided on the key levers. As in the former case each of the key plates m is provided with a hole o for the reception of the pin t of a loose plate a . A series of loose plates a is 70 used in conjunction with this machine; on their upper face they carry the several cipher characters employed and on their lower side a pin t adapted to fit into the hole o in the key-plates m . In order to permit of 75 deciphering with this machine (which can also be used as an ordinary writing machine) the loose cipher character plates a are arranged on the plates m of the key-levers n in accordance with the cipher key; 80 by actuating the type levers according to the cipher text, the latter is transposed by the machine into ordinary text.

It is also possible to provide a single 85 writing machine for writing in cipher and for deciphering. In this case the arrangement is such that both ordinary characters and cipher characters are provided on the type levers in such a manner that—as in the Remington typewriter for small and capital 90 letters—in the normal position of the shift lever h ordinary characters are written while when the shift lever h is depressed cipher characters are written by the machine. 95

As shown in Fig. 5 the ordinary characters and cipher characters are arranged on the type levers of the machine corresponding with the keys and as already described each key-plate is provided with a hole o for the reception of the pin t of a small plate a . When two series of plates a are used one series having the ordinary characters and the other the cipher characters this machine can be employed in 100 the following ways: In the normal position of the lever h the machine can be used as an ordinary type-writing machine for 105

one size of type. If the cipher plates a are placed upon the several key-plates m in accordance with the cipher key, in copying a cipher text the ordinary text will be written when the shift lever h has not been operated. If the plates a presenting ordinary characters are arranged upon the key-plates m in accordance with the cipher key when the shift lever h is depressed the copying of the ordinary text will produce cipher text.

A simple frictional device r (Fig. 5) can be mounted on the frame of the machine for permanently retaining the shift lever h in its depressed position.

Having now described the invention and in what manner the same is to be used, what I claim is:

A typewriter key-plate, marked with any desired character, and having a vertical, angular socket therein, a cap marked with any desired character, and an angular depending pin on said cap, adapted to removably engage said socket, as herein set forth. 20

In testimony whereof I hereunto affix my signature in presence of two witnesses.

SERGE KANSCHINE.
